(57) **CLAIM**

The ornamental design for a drone, as shown and described.

DESCRIPTION

1. Drone

1.1 : Back

1.2 : Top

1.3 : Left

1.4 : General back view

1.5 : Top

1.6 : Perspective

1.7: Back

1.8 : Side view

1.9 : Perspective

1.10 : General view of the back of the drone, consists of a fuselage having the shape of a rectangular parallelepiped with rounded ribs, a convex lower face, a saddle-shaped upper face and a convex rear base; on the front base of the parallelepiped there is a fairing in the form of a quadrangular pyramid with a rounded top and side ribs; two rod trusses are symmetrically attached to the sides of the fuselage: the trusses are equipped with rotors and two cantilever beams are attached; at the top of each beam, two cantilever rods are installed. The rods carry control screws.
